Charles N. Woodward, Atty.

UNITED STATES PATENT OFFICE.

BOHN CHAPIN HICKS, OF MINNEAPOLIS, MINNESOTA, ASSIGNOR, BY MESNE ASSIGNMENTS, TO THE HICKS STOCK CAR COMPANY, OF CHICAGO, ILLINOIS.

CATTLE-GUARD FOR DOORS OF STOCK-CARS.

SPECIFICATION forming part of Letters Patent No. 430,948, dated June 24, 1890.

Application filed May 20, 1889. Serial No. 311,424. (No model.)

To all whom it may concern:

Be it known that I, BOHN CHAPIN HICKS, a citizen of the United States, residing in Minneapolis, in the county of Hennepin and State 5 of Minnesota, have invented certain new and useful Improvements in Door-Guards for Stock-Cars, of which the following is a specification.

This invention relates to double-deck stock-cars, such as are used for the transportation of cattle, horses, sheep, and hogs. When such cars are used for the transportation of small animals like sheep and hogs, they are fitted with a removable deck which divides the car 10 horizontally into two floors or "decks," so that double the number of small animals can be carried than would otherwise be the case, and when large animals like cattle and horses are transported the double deck is removed. 15 Such stock-cars are ordinarily constructed with a doorway on the center of each side for the passage of the animals. If the doors are accidentally left open, there is danger of the cattle escaping and being injured, so that a doorway-guard is usually employed to bar the 20 passage into the car at about the vertical center thereof; also, when the double deck is employed there is a gap left between the edges of the deck and the door, into which the sheep 25 or hogs on the deck are liable to step, and so become injured.

Now the object of the present invention is to provide means for mounting and supporting a doorway-guard to bar the passage when 30 the car is occupied by large animals, and for supporting a platform to bridge the gap between the deck and door when the car is fitted as a double-deck car. In accordance with the 35 invention the same panel serves as the doorway-guard in the one instance and as the bridge in the other.

The invention consists in the means employed for supporting the guard in the two 40 positions in which it is used. This improved means consists in supporting-sockets which are secured on opposite sides of the doorway near the vertical center thereof, each socket being formed with a vertical channel closed 45 at the bottom, which maintains the guard in a vertical position when it is used to bar the

doorway, and with a horizontal channel also closed along its bottom, which maintains the guard at the proper height and in a horizontal position to bridge the gap between the deck and the door.

55

A proper and convenient construction of the improved supporting-sockets embodying the principles of the invention is illustrated in the accompanying drawings, wherein—

Figure 1 is a sectional side elevation of a 60 portion of one side of a stock-car, including one of the doorway-openings provided with the present improvements. Fig. 2 is a plan view in section on the line xx of Fig. 1 with the guard removed. Fig. 3 is a sectional elevation on the line $x'x'$ of Fig. 1, showing the guard arranged to be used in connection with a double-deck stock-car; and Fig. 4 is a similar view showing the guard arranged for use 65 in connection with an ordinary stock-car. Fig. 5 is a detached enlarged perspective view 70 of one of the improved sockets.

A' is the floor-frame; A^2 , the side frames or boarding; A^3 , the door-posts or stanchions; A^4 , the roof; A^5 , one of the doorway-openings, and A^6 one of the sliding doors for covering the openings.

75 Inserted into the inner faces of the door-posts A^3 , on opposite sides of the doorway, are metal sockets B , having a horizontal channel a' and a vertical intersecting channel a^2 . The two sockets on the two door-posts are at equal distances above the floor A' , with their horizontal channels a', a' in the same horizontal plane with the double deck D , when 80 the sockets are employed on double-deck cars. The sockets B are adapted to receive and support the ends of the guard E , either in the vertical channels a^2 , as in Figs. 1 and 85 4, or in the horizontal channels a' , as in Fig. 90 3. Above one of the vertical channels a^2 an inclined groove a^3 is formed in the body of the post A^3 , so that when the guard E is to be inserted into the upright channels one end is placed in one of the sockets a^2 , resting on its 95 closed bottom, and the other end is dropped down through the groove a^3 into the opposite socket a^2 until it rests on the closed bottom thereof. When the guard is to be inserted into the horizontal channels, it is so inserted 100

from outside the car before the door A^6 is closed, the latter thereafter holding it from moving outward, while the closed ends a^4 of the channels a' prevent its removal inward. 5 The guard in its horizontal position rests on the closed supporting-bottom of the channels a' . When the guard E is employed in an upright position, as in Figs. 1 and 4, it can only be removed by lifting it upward at one 10 end—a movement which would not be liable to occur when in use. A chain F connects the guard E at one end to the car-frame, the chain being long enough to permit the free movement of the guard, but effectually preventing its removal from the car. 15

By this simple device an effectual guard is provided to prevent cattle or horses from escaping when the doors A^6 are opened, and which also prevents the animals coming in 20 contact with the doors and forcing them from their bearings. The guard E in this connection serves a double purpose, preventing the cattle escaping when the doors are open and also serving as a guard to the doors when 25 they are closed. Then when used in connection with double-deck cars it is placed in its flatwise position, as in Fig. 3, and thus forms a support for the outer edges of the double deck and also bridges the gap which would 30 otherwise occur in the doorway-openings between the deck D and the doors A^6 . The sockets B are shown embedded in the posts A^3 , their outer faces flush therewith, which is the preferable method; but they might be 35 secured to the inner surfaces of the posts, if preferred.

I claim as my invention—

1. A socket for the doors of stock-cars for the purpose of holding a guard in either a

horizontal or a vertical position, said socket 40 having a vertical retaining-channel with a guard-supporting bottom and a horizontal retaining-channel with a guard-supporting bottom, substantially as set forth.

2. A socket for the doors of stock-cars for 45 the purpose of holding a guard in either a horizontal or a vertical position, said socket having two intersecting channels at right angles to each other, each of said channels having a guard-supporting bottom, substantially as set forth.

3. A socket for the doors of stock-cars for the purpose of holding a guard in either a horizontal or a vertical position, said socket having two intersecting channels at right 55 angles to each other, one being vertical and the other horizontal, each of said channels having a guard-supporting bottom, the vertical channel having an open top and the horizontal channel having its outer end open, substantially as set forth.

4. A stock-car having a doorway and posts on opposite sides thereof, each post having a vertical channel and a horizontal channel, and each of said channels having a guard- 65 supporting bottom, in combination with a guard for said doorway, the opposite ends of which are supported either in said vertical channels or in said horizontal channels, substantially as set forth.

In testimony whereof I have hereunto set my hand in the presence of two subscribing witnesses.

BOHN CHAPIN HICKS.
